UNITED STATES PATENT OFFICE.

WILLIAM PRESTON PHENIX, OF TAHOKA, TEXAS.

MEASURING INSTRUMENT.

936,157.

Specification of Letters Patent.

Patented Oct. 5, 1909.

Application filed March 30, 1909. Serial No. 436,670.

To all whom it may concern:

Be it known that I, WILLIAM P. PHENIX, a citizen of the United States, residing at Tahoka, in the county of Lynn and State 5 of Texas, have invented certain new and useful Improvements in Measuring Instruments; and I do hereby declare the following to be a full, clear, and exact description of the invention, such as will enable others skilled in the art to which it 10 appertains to make and use the same.

This invention relates to new and useful improvements in measuring devices and it is an object of the invention to provide a 15 novel device of this character wherein a multiplicity of devices are contained within the article.

It is also an object of the invention to provide a novel device of this character 20 which may be employed as a level, square, rule, gage, bevel and compasses.

It is also an object of the invention to provide a novel device of this character including a protractor, said protractor affording a hand grasp to permit the ready 25 manipulation of the instrument.

It is also an object of the invention to provide a novel device of this character which will be simple in construction, efficient and advantageous in practice and comparatively inexpensive to manufacture. 30

With the above and other objects in view the invention consists of the details of construction and in the novel arrangement and 35 combination of parts to be hereinafter more particularly referred to.

In describing the invention in detail reference will be had to the accompanying drawings forming part of this specification 40 wherein like characters of reference denote corresponding parts in the several views and in which,

Figure 1 is a view in plan of the invention, said invention being folded in the position to be used either as a bevel or compasses. 45 Fig. 2 is a view taken on the line 2—2 of Fig. 1, and, Fig. 3 is a view taken on the line 3—3 of Fig. 1.

In the drawings, 1 denotes one section of 50 the instrument having formed therewith the protractor 2, said protractor extending from one end of the member to a point intermediate the length thereof. Pivotedly secured by the bolt 3 to the member 1 is a second member 4, the pivotal connection of 55 the member 4 with the member 1 being cen-

trally of the protractor 2 for a purpose which is believed to be obvious. The member 1 is divided by the lines 5 from its pivotal point to an end thereof into graduations 60 while the member 4 is similarly divided. This is done so that the members 1 and 4 may act or serve as a rule more especially when the said sections are so moved one with relation to the other as to be in approximately the same longitudinal plane. The member 1 is provided with a plurality of perforations 7 to permit the device being employed as a gage, it being stated that it will be only necessary to insert a marking instrument through the desired perforation. 65

When the instrument is to be used as a bevel, the member 4 is swung or moved on its pivot 3, the angle of the level being assured by the protractor 2. This same statement applies when the instrument is to be employed as a square, which use is believed to be apparent. To hold the member 4 in the desired position with relation to the member 1, a curved arm 8 is affixed to the 80 member 4 adjacent a longitudinal edge thereof and said arm 8 extends over the protractor 2. In threaded engagement with this arm 8 is a binding screw 9 which contacts with the protractor 2 and effectually binds 85 the member 4 thereto and as the protractor 2 is carried by the member 1, it will be readily perceived that the member 4 will be held against movement.

To expedite the use of the instrument as a 90 square one longitudinal edge thereof is provided with a flange 10 extending at right angles thereto. This flange also permits the instrument to be employed as a level, said flange being provided with an elongated 95 opening 11 beneath which is positioned the liquid glass 12. This glass is carried by a protective metallic casing 13 fixed to the member 4. The member 4 is also provided with an elongated opening 14, so that the 100 bubble within the glass may be seen therethrough.

When the device is not in use the members are swung one above the other and in order that no obstruction may be afforded by the 105 arm 8, an edge of the member 1 is provided with a recess 15 in which said arm will be positioned when the instrument is folded.

The free end of each of the members 1 and 4 is provided with a projecting point 16 110 which permits the device to be used as a compass. It is also to be observed that the end

of the member adjacent the point 16 is recessed as at 17 in order to enhance the operation of the device as such.

Movable laterally of the members 1 and 4 in alinement with the end graduations or lines 5 thereof are the point pins 18 which are held within the brackets 19 by the binding screws 20. These pins are employed to readily mark each two feet measured by the 10 instrument, it being stated that the instrument as disclosed is graduated to measure two feet. In order to permit the device to be readily folded it is to be stated that the pin 18 of one member is on the face opposed 15 to that of the pin of the second member. When the device is being used as a level, the pins 18 are so held as not to project beyond the edges of the members 1 and 4. And to hold the instrument in such a position as to 20 enable it to be employed as a level, the angular foot 21 is secured to the flange 10 of the

member 4, the extended portion of the foot being flush with the lower edge of the flange.

I claim:

An instrument of the character described 25 comprising two members pivotally connected one to the other, means for holding said members against movement on their pivot, a flange carried by one of the members, said flange having an elongated opening, a bubble 30 tube carried by the member having the flange, in a position beneath the opening in the flange and a foot carried by the member having the flange for holding the instrument in position when used as a level. 35

In testimony whereof I have signed my name to this specification in the presence of two subscribing witnesses.

WILLIAM PRESTON PHENIX.
